JOKER CARD FOR A DECK OF PLAYING CARDS

Carolyn H. Edison, West Orange, N. J.

Application October 25, 1949, Serial No. 5,698

Term of patent 3½ years

(Cl. D34—13)

To all whom it may concern:

Be it known that I, Carolyn H. Edison, a citizen of the United States and a resident of the town of West Orange, county of Essex, and State of New Jersey, have invented a new, original, and ornamental Design for a Joker Card for a Deck of Playing Cards, of which the following is a specification, reference being had to the accompanying drawing, forming a part thereof.

The single figure of the drawing is a face view of the joker card for a deck of playing cards, showing my new design.

The card is of no appreciable thickness, and the back of the card may be plain or conventional.

I claim:

The ornamental design for a joker card for a deck of playing cards, as shown and described.

CAROLYN H. EDISON.
